UNITED STATES PATENT OFFICE.

ELWOOD BENNETT, OF KOKOMO, INDIANA, ASSIGNOR OF ONE-THIRD TO
SAMUEL PANABAKER, OF SAME PLACE.

ROTARY ENGINE.

SPECIFICATION forming part of Letters Patent No. 639,504, dated December 19, 1899.

Application filed March 13, 1899. Serial No. 708,904. (No model.)

To all whom it may concern:

Be it known that I, ELWOOD BENNETT, a citizen of the United States, residing at Kokomo, in the county of Howard and State of Indiana, have invented certain new and useful Improvements in Rotary Engines, of which the following is a specification.

The object of this invention is to produce a thoroughly practical engine which may be operated with any fluid as a propelling agent, but which is specially adapted for the use of steam, to produce a rotary engine which will be equally balanced and packed at the joints in a manner to prevent leakage through the joints without creating friction such as will make the operation of the engine impractical, and to provide means whereby the exact centering of the revoluble parts or their position out of center will be indicated on an external portion of the machine.

A further object of the invention is the production of a rotary engine of few parts and which is simple, strong, compact, and durable in its construction.

I accomplish the objects of the invention by the mechanism illustrated in the accompanying drawings, in which—

Figure 1 is a view in side elevation of my invention; Fig. 2, a vertical section on a plane through the center of the driving-shaft of the engine; Fig. 3, a vertical section on the dotted line 3 3 of Fig. 1; Fig. 4, a horizontal section on the dotted line 4 4 of Fig. 1; Fig. 5, an inner side view of the cylinder-head of the engine with the valve-plate removed; Fig. 6, a like view of the same with the valve-plate in operative position; Fig. 6^a, a section of the valve-plate on the dotted line 6^a 6^a of Fig. 6; Fig. 7, a perspective view of the cylindrical piston-carrier removed from the piston; Fig. 8, an end view of the same device shown in Fig. 7; Fig. 9, a perspective view of one of the sliding pistons showing, one of the detachable parts pulled away from its mate and partially sectioned to show the construction better; Fig. 10, a plan view of the outer edge of the sliding piston; Fig. 11, a section on the dotted line 11 11 of Fig. 10; and Fig. 12 a detail of the inner wall of the cylinder, showing the diagonally-bridged outlet for the steam.

Similar letters of reference indicate like parts throughout the several views of the drawings.

A represents the cylinder of the engine, which is supported by the base A'. The cylinder is bored out on three centers, and the driving-shaft B is mounted centrally of the middle bore. The centers of the three bores are in the same plane, which is preferably a vertical one. The shaft B is in two transversely-divided parts, the two adjacent ends of which terminate with the circular disks B', which may be either integral with the shaft or fastened to it in any secure manner—as, for example, by expanding the disk by heat and shrinking it to the unheated shaft by cooling it after its application to the latter. Between the two disks B' is the cylindrical casting B², to which the two disks are securely bolted by means of the screw-bolts b. The casting B² has a diametrical slot to provide a way for the pistons diametrically through the body. The cylindrical sides of the casting B² are turned up to make a close-running fit in the middle bore of the cylinder A. Mounted in the diametrical slot of the body B² are the two pistons C C, which are flat-sided plates that slide in and out in said groove to make a steam-tight joint simultaneously on the two opposite sides of the slotted cylindrical body with the eccentric bores of the cylinder.

To make a steam-tight joint between the walls of the middle bore of the cylinder and the cylindrical sides of the body B², packing-strips b⁵, pressed inwardly by the strips b⁶, which can be set up by the set-screws b⁷, are used, and to keep the packing-strip, which is narrower than the thickness of the piston C, from being forced by the springs into the slot in which the piston is seated, which would be possible, inasmuch as the pistons are drawn into the body B² at the time of passing the packing-strip, the packing-strip will be set obliquely to the straight lines of the body B² and its piston-slot, as shown by the dotted lines in Figs. 1 and 2.

Steam is admitted back of the pistons C C twice in each circuit or revolution of said pistons in the cylinder, once while each piston

is in the upper eccentric bore and once while it is in the lower eccentric bore, and the two pistons are forced out by the radial pressure of steam introduced between the two pistons.

5 The arrangement of the steam-ports and the method of packing to secure a steam-tight joint around the moving parts are important features of this invention.

D are the cylinder-heads, which are alike for both ends of the cylinder. The steam is admitted simultaneously and in the same manner from both ends of the cylinder and also at top and bottom of the cylinder through said ends in order to balance the pressure as much as possible to avoid undue friction in any direction, and inasmuch as both of the cylinder-heads are alike a description of one will suffice for both.

Formed in the top of the cylinder is a steam-chest E, to which steam is supplied through the supply-pipe E', and cored out in the head D and leading from the steam-chest E and emptying into an annular groove or channel D', formed on the inside face of the head close to the bore for the driving-shaft B, is the steam-port D². (See Figs. 2, 5, and 6.) This groove is at the bottom of a central circular indentation of the head and is somewhat smaller in diameter than the indented portion to provide a shoulder outside of it for a bearing or seat for a removable valve-plate F, which is fastened by screw-bolts f over the groove to form a cover therefor. The groove is divided by the walls d into two non-communicating chambers, one of which is for the steam that gives the rotary movement to the engine and the other, which is the smaller and lower one, is to receive the steam to push the pistons out. The groove D' has bosses d' with threaded openings to receive the bolts f, by which the plate F is fastened over the groove. This plate F has two diametrically opposite openings or valves F', each of which is provided with a bushing or ring F², which is forced by the steam-pressure behind it against the side of the piston-head disk B' to make a tight joint, which will prevent the lateral escape of steam, and around it in a suitable groove is a double split metallic packing-ring F³, which prevents the escape of the steam, except through the middle opening.

Back of each of the sliding pistons C C, formed in the body B², are a pair of separate and deep grooves b⁴, which communicate at their bottoms with the annular grooves b' in the adjacent sides of the disk B', and the rotation of the disk B' brings the grooves b' at regular intervals over the valves F'. As long as the grooves are over a valve the steam is free to issue into the groove b' and thence through the groove b⁴ into the cylinder back of the sliding piston. As shown in Figs. 7 and 8 and in dotted lines in Fig. 3, the grooves b' have inwardly-projected and rounded ends to give quick admission and cut off of steam.

Any water which may gather from the con-

densing of the steam in the cylinder is carried off through the drain-pipes P, having the relief-valves p, by which they are opened and closed.

70 The steam is exhausted from the cylinder through the ports G into the chamber G' under the cylinder (see Fig. 3) and is carried off from there through the pipe G². In order to lessen the wear on the piston, which would be excessive if the openings for the exhaust were straight openings, I prefer to bridge them diagonally in the manner as shown in dotted lines in Fig. 2 and in full lines in Fig. 12, in which the bridges are shown at g.

80 The steam-pressure from the boiler to the engine is regulated by means of the governor H⁷, Fig. 1, of usual construction and operation.

The disks B' are sufficiently less in diameter than the body B² to form a shoulder, into 85 the seat formed by which the packing-ring H is placed, and the cylinder-head has an annular depression to receive the packing-ring. It extends beyond the eccentric bores of the cylinder, and by pressure of steam against the 90 outer side of it it is forced over to prevent leakage of steam into or from the cylinder at those points.

Figs. 2 and 4 show the preferred packing around the shaft B and between it and piston-heads. It consists of the threaded ring l, which is screwed onto the threaded section of the shaft. The threads make a steam-tight joint on the inside of the ring, and to prevent the escape around the outside of the ring I 100 use the inner split collar i and the two split collars i' outside of it, (see Fig. 5,) which pack the joint.

The successful operation of my engine depends very largely upon the maintenance of 105 the shaft B and piston-carrier attached thereto in position concentric with the middle bore of the cylinder, and this depends on the nature of the bearings to support the outer ends of the shaft and upon the means for indicating when the shaft is out of center and for readily correcting any such displacement. J are brackets which are projected laterally from the cylinder-heads. They have openings through which the shaft B is projected, 110 with four equidistant set-screws j arranged in diametrically opposite pairs. The shaft-openings through the brackets J are large enough to receive the cylindrical boxes J' and allow considerable play around them on all sides, 115 whereby by changing the set-screws j, which contact with the boxes to hold them in a fixed position, the position of the boxes can be shifted in any desired direction and any displacement corrected. A lining of antifriction 120 metal between the box and shaft is shown at j².

The outer or hubbed ends of the brackets J around the shaft are turned up concentrically with the center of the middle bore of the cylinder, and a disk K of exactly the same 130 diameter is fastened to the shaft in close contact with the turned-up hub. When the shaft

B is running true with the center of the cylinder, the face of the disk K will be even with the face of the hub on the bracket J at all points and any displacement of the shaft will be indicated by a break in the alinement of the two surfaces.

As described thus far the construction of the two cylinder-heads is the same; but as it is only necessary to have one inlet for the steam into the space between the two sliding pistons only one of the heads will need to be provided with a port for the introduction of this steam.

I will now describe the manner of introducing the steam under the pistons and then will describe the construction of the pistons themselves.

L, Figs. 1 and 3, is a pipe which connects between the governor H⁷ and the steam-generating boiler with the supply-pipe E' and has its own reducer L', whereby a predetermined steam-pressure may be had from the pipe independently of the greater pressure from the boiler required to run the engine. This pipe L connects with the port l', (see dotted lines in Fig. 3 and full lines of Fig. 4,) which port empties into the lower compartment of the channel D', from whence it issues through the port F⁷ in the valve-plate F into the annular groove f⁷, formed in the bore of the ring around the shaft. Leading from this groove f⁷ and passing through the shaft B and thence into the chamber between the two sliding disks is the port B⁷. A constant pressure is thus obtained against the pistons to press them out into contact with the bores of the cylinder. A drain-pipe W, having an automatic relief-valve w of common form, is provided to carry off any water that may condense from steam between the ends of the sliding pistons C C.

M, Figs. 2, 4, 7, and 8, is a packing-ring which is seated in an annular groove around the shaft in the outer sides of the disks B' to keep the steam from passing either way between the disks B' and the valve-plate F. The ring is pressed out against the plate F by the springs m, and it is provided with an outside groove, in which the split packing-ring m' is seated. This packing-ring could obviously be seated in the plate F instead of being in the disk B' if desired.

The pistons C are in two transversely-divided parts to permit of endwise extension to make a tight joint against the packing-rings between which they run. Both of the adjacent edges are provided with the grooves C' to receive the tongue C², and midway of their widths are the notches C³ to receive the expanded portion C⁴ of the tongue. The purpose of the tongue C² is to close the joint between the two parts of the piston against the leakage of the steam therethrough from one side of the piston to the other, and the purpose of the enlargement C⁴ is to prevent the passage up through the joint or its grooves of

the steam below the piston. Grooves C⁵, as shown, permit of the introduction of the steam from below between the two parts of the piston to press the parts over against the packing-rings at their ends. Chambers C⁶, opening toward the center of the shaft, are formed in each of the two sections of the piston, and these chambers communicate through the holes C⁷ with the grooves C⁹ in the ends of the pistons. The object of this is to admit enough steam to the groove to partly resist the pressure from the middle of the piston in order to prevent undue friction of the parts.

Having thus fully described my invention, what I claim as new, and wish to secure by Letters Patent of the United States, is—

1. A stationary cylinder having two or more communicating bores eccentric to each other, a revoluble shaft carrying a cylindrical body having one or more radial ways, a piston or pistons sliding in said way or ways, means for forcing the piston or pistons out into constant contact with the inside walls of the cylinder, a steam-chest supplied with steam from a generator, cylinder-heads, chambers in the cylinder-heads, ports leading from the steam-chest to the chambers, ports leading from the ends of the cylindrical piston-carrying body, said ports discharging back of the piston or pistons through the cylindrical sides of said body, valve-openings leading from the chambers in the cylinder-heads and discharging against the piston-carrying body in the paths of the ports in the latter, and ports for the discharge of the exhaust-steam from the cylinder, substantially as described and specified.

2. In a rotary engine, a cylinder having a circular central bore and a crescent-shaped enlargement above and below the central bore, a cylindrical piston-holding body revolubly mounted in the central bore and making a close fit therewith said body having a diametrical slot therethrough, a pair of sliding pistons mounted in the opposite ends of said slot and means for pressing the pistons out into constant contact with the inside walls of the cylinder, said piston-carrying body having a pair of ports opposite each piston, extending from the flat ends of the body to and through the cylindrical walls thereof, a covered groove or chamber in the cylinder-heads adjacent to the ends of the piston-carrying body, a pair of diametrically opposite valve-openings located in the paths of the port-holes in the sides of the piston-carrying body and affording communication at intervals during each revolution between the chamber in the cylinder-head and the said ports, a steam-chest connected with a steam-supply and ports leading from the steam-chest to the groove or chamber in the cylinder-heads and exhaust-openings for the escape of the dead steam from the cylinder, all substantially as described and specified.

3. The combination, with a cylinder-head

- of a rotary engine having a groove or channel around the shaft-opening in said head and ports connecting the channel with the steam-chest of the engine, of a plate removably secured over the channel to form a cover therefor, said plate having diametrically opposite openings, substantially as described and specified.
4. A cylinder-head for rotary engines having a chamber connected by ports with the steam-chest of the engine and a cover for said chamber having openings therein for the discharge of steam from the chamber, said openings having packing-rings to contact with the adjacent revolving piston-carrying body and prevent lateral leakage around the openings, substantially as shown and described.
5. In a rotary engine, a cylinder having a circular central bore and crescent-shaped enlargements above and below said central bore, a cylindrical body for holding pistons, revolvably mounted in the central bore and making a close fit therein, said body having reduced ends, a plate wide enough in diameter to seat against the ends of said body at the reduced portions and extending beyond the crescent-shaped extensions far enough to overlap the ends of the cylinder, said plates being circular in form and held against the ends of the cylinder and shoulders of the body by steam thereby forming a tight closure for the crescent-shaped extensions of the cylinder when the engine is at work and forming a closure capable of yielding to uneven expansion when all parts of the engine are not heated to a uniform temperature as when the engine is being started cold, substantially as specified.
6. In a rotary engine, a cylinder having a central circular bore and crescent-shaped enlargements diametrically opposite the central bore, a piston-holding body revolvably mounted in the central bore, said body having a longitudinal slot passing diametrically through it, a pair of sliding pistons in opposite ends of said slot cylinder-heads having an annular groove divided by a partition into two chambers one of which is connected with the steam-chest of the engine a steam-chest, means for supplying steam to said chest, and a governor for regulating the pressure of the steam, means for supplying steam to the other or second chamber, said means taking its steam-supply between the above-mentioned governor and the steam-generating boiler, means for regulating the pressure of the supply of steam to the second chamber, a port leading from the second chamber into the slot between the two sliding pistons, a cover for each of the chambers in the cylinder-heads said covers having a pair of diametrically opposite openings leading into the first-mentioned chambers, said openings being supplied with packing-rings as described, ports starting from the ends of the piston-carrying body and registering at each revolution of the body with the openings to the chambers, said ports in the piston-carrying body terminating back of the sliding pistons substantially as shown, and exhaust-openings from the cylinder for the escape of the spent steam.
7. In a rotary engine having a revoluble body, carrying a pair of sliding pistons, a steam-supply for driving the pistons in direction to rotate the body and a separate means for supplying steam for forcing the pistons apart, the said body having ports near its outer face for the passage of the steam back of the pistons and other ports through the hub of the body for introduction of steam between the pistons, and a packing-ring seated in a groove of the body between the two sets of ports to prevent the leakage of steam from one set of ports to the other substantially as shown and described.
8. In a rotary engine, the within-described packing between the revoluble shaft and the cylinder-head of the engine, comprising a cylinder-head with an opening for the shaft considerably larger than the shaft, a shaft having a screw-threaded portion lying in said opening, a nut with a screw-threaded opening said nut screwing onto the shaft and thereby being drawn into the opening in the cylinder-head and split-metal packing-rings in the opening against the inside of the nut to pack the joint between the nut and the cylinder-head the inner one of said rings not touching the revoluble shaft, substantially as shown and described.
9. In a rotary engine, a cylinder having a circular bore and one or more crescent-shaped extensions therefrom, a piston-carrying body revolvably mounted in the central bore and having a pair of sliding pistons, said body being supported by lateral shaft extensions, boxes in which the shaft is supported, frames or brackets to support the boxes having four equidistant radial set-screws to support each box to permit of adjustment of the latter in all directions, said shaft extensions and an index to determine when the shaft is in central alignment with the cylinder said means consisting of a hub on the outer end of the frame or bracket which supports the boxes and collars bolted to the shaft outside of the boxes, said collar and hub being turned to equal radii, substantially as shown and specified.
10. A flat-sided piston divided transversely into two parts the adjacent ends of said parts being notched and grooved, a key fitting into the notches and grooves to make a tight-jointed connection between the two parts of the piston and ports between the ends and the key for the introduction of steam to expand the piston, substantially as described and shown.
11. A piston having recessed ends and steam connection with said recesses, said piston being

ing divided transversely into two parts, ports
for the introduction of steam between the
parts to expand the piston in the direction of
its length and means for making a steam-
5 tight connection between the divided parts of
the piston, substantially as described and
shown.

In witness whereof I have hereunto set my
hand and seal at Indianapolis, Indiana, this
20th day of February, A. D. 1899.
